HEAD SUPPORT FOR DIAGNOSTIC APPARATUS

BACKGROUND OF THE INVENTION

The present invention relates to headrests or supports which are generally used on diagnostic apparatus, particularly eye examination apparatus, such as slit lamp apparatus and similar devices. When conducting an examination of the eye, for instance to determine certain critical properties thereof, it is necessary that the head remain reliably immobile in a prescribed position. Due to the greatly dissimilar shapes of heads in the forehead and temple portions, problems commonly arise in properly fitting the head-holding member to a patient in a comfortable and effective manner.

SUMMARY OF THE INVENTION

It is accordingly an object of the present invention to provide a head support for a diagnostic apparatus which reliably and precisely positions a subject's head with reference to said apparatus without causing the subject any discomfort.

It is a further object to provide such a device which is quickly applied to the forehead and temple portions of the head of the subject regardless of the contour of those portions.

Further objects and advantages will be found in details of construction and arrangement thereof by reference to the following specification and the accompanying drawing.

BRIEF DESCRIPTION OF THE DRAWING

FIG. 1 is a plan view showing a preferred form of the present invention, and

FIG. 2 is a rear elevational view of said invention.

DESCRIPTION OF PREFERRED EMBODIMENT

In the preferred embodiment of the present invention, as shown in FIG. 1, there is provided a head support which is generally designated by the numeral 10. The support device 10 is held on a base member 11, which in most cases is part of the diagnostic apparatus to be served, by machine screws, one of which is shown at 12.

The head support device 10 comprises a baseplate 13 whereon a chin rest 14 is mounted centrally thereon, said chin rest being adjustably held above the baseplate 13 by means for a jackscrew 15 which is rotatably held in a bore 16 formed in the baseplate 13. The downward force on the chin rest 14 is transmitted from the jackscrew 15 through an adjusting nut 17 wherein the screw is threaded and is thereby transmitted to the baseplate 13.

Further comprising said chin rest 14 is a metallic platform 18 whereon a concave nonmetallic chin pad 19 is held demountably by means of a pair of opposite spring detents 20 and 21 which engage in corresponding notches 22 and 23 formed in the platform 18. Along the front side of the chin pad 19 is formed a vertical flange 24 which functions as a chin stop, the chin rest serving to locate the patients' head as indicated by dotted lines at 25.

According to the present invention, means are provided for firmly and reliably holding the upper part of the head 25 against sideward and forward lateral motions, said means comprising a pair of parallel vertical posts 26 and 27 which are adjustably secured by clamping screws 28 and 29 in the bores 30 and 31 formed at the outer ends of the baseplate 13 as shown in FIG. 1.

At the upper end of each post 26 and 27 is secured an arm, the pair of arms being designated by numerals 32 and 33. Said arms extend generally toward each other in a forward direction so that one is inclined to the other symmetrically at an inclined angle of about 90° or more so as to provide a space for the head 25 as partially shown by dotted lines in FIG. 1.

Near the outboard end of the arms 32 and 33 are pivotally mounted individually a pair of contact or rocker blocks 34 and 35 which have curved locating surfaces 36 and 37 formed thereon. Locating surfaces 36 and 37 approximately are shaped to conform to the average curvature of forehead 25 just above the brow line and said surfaces normally lie on a common circle in the preferred form of the invention.

The contact or rocker blocks 34 and 35 are provided with horizontal bosses 38 and 39 which are held pivotally within free fitting recesses 40 and 41 formed in the respective arms 32 and 33 and held therein by the respective pivot pins 42 and 43. As shown in FIG. 1, the clearance spaces between the blocks contact or rocker blocks 34 and 35 and their respective recesses 40 and 41 are sufficient to permit restricted pivoting movement of the contact or rocker blocks for the purpose of conforming the locating surfaces 36 and 37 to the contour of different heads. Simple means such as the leaf springs 44 and 45 secured to the backs of the contact or rocker blocks 34 and 35 are provided to maintain the contact or rocker blocks normally erect in their recesses.

In order to comfortably accommodate head contours which vary greatly in shape and size, a flexible headband 46 is provided which extends around the forehead in contact therewith above the brow line. The ends of the headband 46 are secured 25 by any preferred means such as the screws 47 and 48 which pass through holes in the ends of the headband and are threaded into tapped holes in the contact or rocker blocks 34 and 35 as shown in FIG. 1.

Further accommodation for different shapes and sizes of heads 25 may be made by loosening the lockscrews 49 and 50 which hold the arms 32 and 33 on the upright posts and adjusting the angularity of the arms, and additionally by using headbands 46 of different lengths.

When making vertical adjustments in the location of the headband 46, the thumbscrews 28 and 29 are released so that the arms 32 and 33 together with the crossbar and its attached headband may be raised or lowered, following which the thumbscrews are tightened again.

From the foregoing description it will be appreciated that 40 the present invention provides a headrest which supports the head of a patient comfortably and reliably regardless of the contoured shape thereof and requiring no adjusting screws except for elevation.

Although only a preferred form of the invention has been 45 shown and described in detail, changes in the form and arrangement of the parts thereof are possible without departing from the spirit of the invention as defined in the claims appended herebelow.

We claim:

1. A device for support a head in a diagnostic apparatus having a base and a support frame said frame including a pair of upright posts and a chin rest for said head located between the posts, said device comprising:
a pair of horizontally disposed support arms directed angularly toward each other each affixed at one of its ends to a respective one of said posts and projecting toward each other, and toward the temples of said head,
a pair of rocker blocks having bosses formed thereon, each boss being freely fitted within one of said recesses,
pivot means cooperatively engaging said bosses and said support arms to allow said rocker blocks to pivot within said recesses,
a flexible head strap extending between the rocker blocks for being disposed about the forehead portion of said head in an arcuate shape, and
means for anchoring the opposite ends of said flexible head strap individually onto said rocker blocks.
